UNITED STATES PATENT OFFICE.

MICHAEL HÄBERLE, OF RICHMOND HILL, NEW YORK.

WINDOW.

Application filed December 9, 1925. Serial No. 74,338.

The invention relates to windows and provides for a close joint when the window is shut to exclude air, dust and dampness and to admit of adjustment of the window when required for ventilation and furthermore, to facilitate cleaning without the inconvenience and hazard attendant upon the mounting of the sill to reach parts of the window when the sash receives a sliding movement only.

10 While the drawings illustrate a preferred embodiment of the invention it is to be understood that in adapting the means to meet specific needs and requirements the design may be varied, and such other changes in 15 the minor details of construction may be resorted to within the scope of the invention as claimed, without departing from the spirit thereof.

For a full understanding of the invention 20 and the merits thereof, reference is to be had to the following description and the drawings hereto attached, in which,—

Figure 1 is a front view of a window illustrative of the invention and having parts 25 broken away.

Figure 2 is a vertical transverse sectional view on the line 2—2 of Figure 1 looking in the direction of the arrows,

Figure 3 is a horizontal sectional view on 30 the line 3—3 of Figure 1,

Figure 4 is a horizontal sectional view on the line 4—4 of Figure 1, showing the sash partly open,

Figure 5 is a detail sectional view on the 35 line 5—5 of Figure 1.

Figure 6 is an enlarged sectional view on the line 6—6 of Figure 2, and

Figure 7 is an enlarged detail sectional view on the line 7—7 of Figure 3.

40 Corresponding and like parts are referred to in the following description and designated in the several views of the drawings, by like reference characters.

The window frame or casement may be of 45 any preferred construction, according to the specific adaptation and requirements and includes side stiles 1 and 2, an upper cross piece 3 and a sill 4. The window frame or casement may be supplied with any number and type of sashes and, in the present instance, it includes a lower sash 5 and an upper sash 6. The lower sash 5 is mounted for a twofold movement, the one sliding, the other pivotal. The upper sash 6 is mounted to swing inwardly and downwardly from

its upper edge and is hinged at its lower edge to a transom 7. A suitable fastening is provided to secure the sash 6 when closed and the same comprises a plate or keeper 8 attached to the upper cross piece 3 and a spring actuated latch 9 attached to the top cross bar of the sash 6. A close-joint is obtained between the transom 7 and the bottom cross-bar of the sash 6 by means of a tongue 10 and a matching groove 11, the one being formed on the transom 7 and the groove 11 being plowed in the bottom cross bar of the sash 6. A rabbeted joint 12 results in a close fit between the top bar of the sash 6 and the cross piece 3. Metal strips 13 are attached to the side stiles of the sash 6 and longitudinal edge portions project and overlap companion metal strips 14 attached to the upper portion of the side stiles 1 and 2, thereby insuring a close joint at the sides 75 of the upper sash 6.

The sash 5 is mounted to receive a vertical sliding movement and a pivotal movement and is counterbalanced by means of a weight 15 and flexible connection 16, such as a chain or sash cord, which passes around a guide pulley 17 applied to the upper end of the side stile 2.

A guide rod 18 is mounted upon the side stile 2 and is attached to brackets 19 which in turn are made fast in any determinate way to the stile 2. Guide sleeves 20 attached to a side stile of the sash 5 receive the rod 18 upon which they are free to slide and turn, thereby admitting of the sash 5 having a free vertical movement and a horizontal swinging movement. A groove 21, similar to the groove 11, is formed in the side stile 2 to receive a matching tongue 22 projecting laterally from the hinge stile of the sash 5 so as to secure a close joint when the sash is shut. The side stile of the swinging edge of the sash 5 is rabbeted and a metal strip 23 is attached thereto and an edge portion thereof projects across the rabbet to enter a groove 24 of the side stile 1 thereby insuring a close joint at the swinging edge of the sash 5 when closed.

A metal strip 25 applied to the top cross bar of the sash 5 coacts with a companion metal strip 26 attached to the lower side of the transom 7, both metal strips having edge portions projected and bent so as to overlap, as shown most clearly in Figure 2, thereby insuring a close joint between the 110

top of the sash 5 and the transom 7. The bottom cross bar of the sash 5 is adapted to rest upon the sill 4 in the rear of the stool 27 and in this manner a close joint is assured between the bottom of the sash 5 and the sill 4.

A lift 28 is applied to the bottom cross bar of the sash 5 for convenience of manipulating the sash when raising, lowering, or swinging the same. A suitable lock is provided for securing the sash 5 in closed position and, as shown, the same consists of a plate 29 attached to the transom 7 and a pivoted latch 30 applied to the top cross bar of the sash 5. When the sash 5 is lifted to clear the stool 27 it is prevented from swinging inward by means of a stop 31 applied to the stile 1 and this stop is disposed at one end of a lever 32 which is pivotally mounted intermediate its ends to a stud projecting inwardly from a face plate 33 which is let into the stile 1, the opposite end of the lever 32 having a push button 34 associated therewith and mounted in a boss 35 projected laterally from a face plate 33. When the stop 31 is pressed inwardly it clears the sash 5 and admits of the latter being swung inwardly, as indicated in Figure 4. A pin 36 depending from the side stile adjacent the hinged edge of the sash 5 is adapted to engage any one of a plurality of openings 37 formed in a plate 38 attached to the sill 4 of the window frame, or casement, so as to secure the sash at the required adjusted position. A stop 39 projected upwardly from the plate 38 limits the inward swing of the sash 5.

As previously stated, the top sash 6 is hinged to the transom 7 so as to swing inwardly and downwardly from its top edge and when shut, the sash 6 may be supported by one of a plurality of stops 40 which are disposed in vertical relation upon the stile 2 which is recessed, as shown most clearly

in Figure 6, to receive the stops 40 and a face plate 41 to which the stops are pivoted. Each of the stops 40 projects laterally from one end of a lever 42 which is pivoted intermediate its ends to a stop 43 projected laterally from the face plate 41, the opposite end of the lever 42 being supplied with a button 44. The stops 40 and buttons 44 are adapted to operate through suitable openings in the face plate 41 and when the stops 40 are projected the buttons 44 are retracted and when the stops 40 are pressed inwardly the buttons 44 are moved outwardly in position to be conveniently pressed upon by a digit of the hand.

It will be understood from the foregoing that the invention may be readily adapted to any type or construction of window and insures a close joint between the frame or casement and the sash, and at the same time, admits of the sash having either a pivotal or a combined pivotal and sliding movement, so that ventilation may be obtained, or the glass rendered easily accessible for cleaning and the sash may be held in the required adjusted position.

Having thus described the invention, I claim:

The combination with a window frame having a fixed transom and a sash disposed above the transom and hinged thereto to swing inwardly and downwardly, of a plurality of vertically disposed stops located in a recess formed in a stile of the frame, a plate closing the recess of the stile, vertically arranged levers pivoted intermediate their ends to the plate and having the said stops at one end thereof, and buttons at the opposite end of the levers for projecting the stops into operative position.

In testimony whereof I affix my signature.

MICHAEL HÄBERLE. [L.S.]
